UNITED STATES PATENT OFFICE.

MAURICE SWITZER, OF NEW YORK, N. Y.

DESIGN FOR A PAPER-CUTTER.

No. 38,886.

Specification for Design.

Patented Nov. 19, 1907.

Application filed October 1, 1907. Serial No. 395,468. Term of patent 3½ years.

To all whom it may concern:

Be it known that I, MAURICE SWITZER, of New York city, county of New York, State of New York, have invented a new, original, and ornamental Design for Paper-Cutters, represented in the accompanying drawing.

The figure is a plan view of a paper cutter, showing my new design.

What I claim is:—
The ornamental design for a paper cutter as shown.

MAURICE SWITZER.
